UNITED STATES PATENT OFFICE.

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

COMBINED TYPEWRITING AND COMPUTING MACHINE.

Application filed September 26, 1925. Serial No. 58,764.

This invention relates to combined typewriting and computing machines, and more particularly to means for facilitating the reading of one of two or more co-operating registers in the computing mechanism by the use of automatically controlled shutters for the registers.

Sometimes machines of the well-known Underwood-Hanson type, are equipped with 10 a second register or totalizer having dials with reversed numerals and running in the same direction as the dials of the regular register, thus effecting a well-known negative accumulation in this register. Since in 15 such type of machines the two totalizers are aligned end to end, and since the general appearance of the two totalizers is the same, it is not easy to distinguish the regular computations in one register from the overdraft 20 in the other, the operative being liable to read the amount from the wrong register.

The purpose of this class of machines is to show the correct reading of an overdraft instead of the complementary reading as 25 it would appear when a greater amount is subtracted from a lesser amount, such as, for instance, in handling bank accounts.

One of the features of this invention relates to means whereby the possibility of the 30 operative mistaking an overdrawn amount for a positive quantity and thus wrongly writing the amount to clear the machine, is obviated by the simple expedient of covering the regular register when a negative 35 amount appears on the overdraft register, and, conversely, by keeping the overdraft register normally covered.

Although the scope and the importance 40 of this invention cannot be exaggerated, since it absolutely precludes the possibility of errors when copying from the registers, the means by which the invention is carried out is so simple that its reliability is assured.

In carrying out the invention, there is 45 provided a shutter-plate straddling a pair of registers and rotatably mounted upon the register-shaft. Said plate is common to both registers, but is designed in a manner to afford the blinding of one of the registers 50 while exposing the other. In these machines the dial of highest denominational position in the regular register is, at all times, at "0" position, except when an algebraic summation is effected in the regular 55 register, in which case, for reasons well

known in the art, the digit-dial-wheel of highest denominational order will stop at the "9" position. Advantage is taken of this condition in the automatic operation of the shutter-plate; the plate being moved to 60 cover the regular register when the last or highest denominational wheel passes from the "8" to the "9" position, and is again released if the wheel moves to the "0" position. It will be clear from the foregoing description that the regular register will be 65 covered to permit the reading of the overdraft register only when the last or highest denominational wheel is stopped in the "9" position, and that such position of said 70 wheel is only obtained when a greater amount is subtracted from a lesser amount, thereby running a negative amount into the overdraft register.

Other features and advantages will here- 75 inafter appear.

In the accompanying drawings,

Figure 1 is a plan view of a front section of an Underwood combined typewriting and computing machine, showing a regular and 80 overdraft register in front of the keyboard.

Figure 2 is a cross-sectional view, in elevation, of the regular register, showing the shutter in its normal position of closing the 85 overdraft register or corresponding to Figure 4.

Figure 3 is a view similar to Figure 2, but shows the shutter closed to the regular register, or corresponding to Figure 5, to permit the reading of an amount in the overdraft register. 90

Figure 4 is a plan view, showing both the regular register and the overdraft register, the former showing a positive quantity ac- 95 cumulated therein.

Figure 5 is a plan view, showing a negative quantity in the overdraft register, the shutter being positioned to cover the regular register.

In the Underwood-Hanson typewriting and computing machine partly illustrated in Figure 1, there are provided two registers, or totalizers, the two being synchronized by mechanism, including pin-bars actuated 105 by a general operator as disclosed in the patent to F. A. Hart, dated October 15, 1918, No. 1,281,953. It will be obvious, however, as the specification is read, that any number of pairs of registers similarly 110

synchronized could be provided in a machine, or that a pair of such registers could be co-ordinated with other registers, not necessarily having an associated overdraft 5 register.

As shown in the present invention, there are provided two registers, one indicated by the letter "R" representing the regular register into which amounts are accumulated 10 and subtracted in the regular manner, and another register indicated by the letters "OD" into which the overdrafts or negative quantities are accumulated. Since the two registers are controlled by the same setting 15 of the pin-bars in the machine, it will be apparent that in order to add negative quantities in the "OD" register, the dial-digits thereof have to be reversed.

Normally, the two registers are a "0" 20 position, as shown in Figure 1, and only the regular register is visible to the operative through an opening 10, the other register being covered by a shutter 11. Said shutter extends substantially the full width of the 25 two counters, so as to straddle both, and is provided with ears 12 at the ends, rotatably supporting the shutter upon a register-shaft 13. Since the two registers are mounted on the same shaft and the openings through 30 which the registers are rendered visible are in the same line, it will be apparent that the shutter must be offset to simultaneously expose one of the registers while covering the other. As shown in Figure 1, the "OD" 35 register is provided with an opening 14 to render the register visible, but cannot be read because of the shutter closing the opening.

Upon accumulating the numeral "4" in 40 the register "R" the same number will appear through the opening 10 in the dial of lower denominational order, but, since the associated register "OD" is run in the same direction, and, since the numbers on the face 45 of the dial are reversed, a complementary number plus one will appear through the opening 14, although the number will be invisible to the operative, because of the shutter 11 being, at this time, in front of the dial. If there were no shutter, the operative would be liable to erroneously take 50 the "6" and the preceding "9's" appearing in the "OD" register as a positive quantity, a condition which is eliminated because of 55 the automatic operation of the shutter.

Referring to Figure 5, in which the registers are shown at the end of a computation representing the subtraction of "6" from the register "R" having "4" accumulated therein, it will be noted that, for reasons well known 60 in the art, when subtracting a greater number from a lesser number in the register, a series of "9's" appear on all the dials of higher denominational order, and, consequently, it would be confusing to have these

"9" dials in view, when reading the overdraft register "OD", in which, because of the mechanism provided in the machine, the figure "2," preceded by "0's," will appear representing the true algebraic summation 70 of "4-6=-2."

Since the principle of operation of this invention may be understood by analysis and by reference to the foregoing description, it will be well to now pass on to the description 75 of the mechanical elements required to carry out the invention. Advantage is herein taken of the fact that, when adding, or when subtracting a lesser from a greater amount, the highest denominational positioned dial-wheel 15 of the "R" register always comes to rest at "0" position, whereas, when an algebraic summation is performed, that is to say, when a greater amount is taken 80 from a lesser amount registered in "R", said dial-wheel 15 always comes to rest at "9", as shown in Figures 5 and 3.

This being a fact in the Underwood machine, it is only necessary to provide the shutter with a spring-detent finger 16, fast 90 thereto by means of rivets 17 and engageable with a peripheral lug or tooth 18 on the dial-wheel 15. Said tooth engages an offset portion 19 of the detent-finger piece 16 upon reaching the "8" position of the wheel 15, 95 and, because of the contact between the detent 16 and the tooth, the shutter is carried, with the wheel, to the "9" position, as shown in Figure 3, wherein the "R" register is covered by the shutter. Upon rotating 100 the wheel 15 further, either to restore it to its normal "0" position when a greater amount is thrown into the "R" register or to clear said register, then, owing to the resiliency of the detent-finger 16, the tooth will 105 pass under said finger, thus permitting the rotation of wheel 15, while, at the same time, permitting a spring 20 to retract, thereby normalizing the position of the shutter to expose the register "R". However, if a 110 fresh negative amount is added to the regular register, the wheel 15 will again be stopped at the "9" position, thereby opening the shutter for overdraft reading.

One side plate or ear 12 of the shutter 11 is provided with a bi-forked extension having two prongs 21, engageable with a stop-pin 22 fast to the side plate 23 of the register; the pin 22 limiting the travel of the shutter, which is held in its normal position, as shown in Figure 2, by means of the spring 20 secured to a stud 24, fast to said plate 23, and to a stud 25, fast to the shutter. 115

Sometimes it may accidentally happen that the total amount accumulated in the "R" register will carry over the wheel 15 up to the "9" position thereof, and in such cases the operation of the shutter would, of course, be incorrect, since it would shift the shutter to overdraft reading when the 120 125 130

correct amount should be read on the regular register. To avoid such inaccurate timing of the shutter, it is proposed to assemble the register "R", with a blank dial, or one more dial than is necessary for a given computing capacity of the register, thereby eliminating the possibility of such a condition happening in normal operation, because then, at no time, would the accumulated amounts reach the "9" position of the wheel 15.

It will be understood that the two registers are in alignment in being assembled upon the same shaft and actuated simultaneously by duplicate denominational 15 digit-selecting devices similar to those shown by the patent to Norin, dated August 17, 1920, No. 1,350,173; that in the Underwood-Hanson machine when indexing for subtraction all the "9" pins are set, 20 and later when the digits are indexed on the dial-driving rack-bars, the "9" pins on each bar are restored to normal positions, and upon actuation of the general operator, the successive digit-wheels of the higher 25 denominations, in which no digits have been set up, will be given complete revolutions of nine steps plus a single step, due to the carry-over mechanism fully described in the patent to Gumprecht, dated November 30, 1918, No. 1,285,134; that the denominational racks associated with the rotation of the blank or dummy digit-wheel 15 may be provided with a single index-pin corresponding to the "9" pins of the other rack-bars and settable with these "9" pins when subtraction is effected; and that each time the general operator is actuated with a subtraction-setting for a positive registry in the register "R", the wheel 15 will be given 40 a complete revolution, and while the lug 18 thereon will engage the finger 16 and carry the shutter under the opening 10, said lug will ride under the finger 16 and release the closed shutter to the action of the 45 spring 20 that restores said shutter to register-reading position; that when a negative result is registered, the wheel 15 will lack one step of a complete revolution and the normal arrested position for the shutter will be under the opening 10 to shut off the 50 reading of the register "R"; and that the registers are provided with a shutter that is longitudinally co-operative with both registers "R" and "OD" through offset shutter-sections, which, through their relative displacement, simultaneously and automatically expose the reading of one register

while closing the sight-hole of the other register, and vice versa.

Variations may be resorted to within the 60 scope of the invention, and portions of the improvements may be used without others.

Having thus described my invention, I claim:

1. In a combined typewriting and computing machine having a plurality of registers on which subtraction may be performed by adding the complement of the subtrahend, the dials moving in the same direction for both addition and subtraction but the dials 65 of one register having its digits running in reverse direction from that of the other register and the dial of highest denomination of one register having an obstruction thereon, said machine also having a shutter movable to cover said one register by the movement of said highest denomination dial to "9" position; the combination of yieldable means operable by said obstruction to close said shutter, said yieldable 70 means permitting said dial to pass through the "9" position independently of the shutter, means for arresting the shutter in its closed position and a spring for returning the shutter when released from said obstruction, said shutter being constructed and operative to cover the registers in alternation.

2. In a combination typewriting and computing machine having a plurality of axially aligned registers on which subtraction may be performed by adding the complement of the subtrahend, the dials moving in the same direction for both addition and subtraction but the dials of one register having its digits running in reversed direction from that of the other register and the dial of highest denomination of one register having an obstruction thereon, said machine also having a shutter associated with both registers and movable to cover said one register by the movement of said highest denomination dial to "9" position; the combination of yieldable means operable by said obstruction to close said shutter said 90 yieldable means permitting said dial to pass through the "9" position independently of the shutter, means for arresting the shutter in its closed position and a spring for returning the shutter when released from said obstruction, said shutter being laterally offset at its center and operative to cover the registers in alternation.

JESSE A. B. SMITH.

CERTIFICATE OF CORRECTION.

Patent No. 1,705,073.

Granted March 12, 1929, to

JESSE A. B. SMITH.

It is hereby certified that the above numbered patent was erroneously issued to "Underwood Elliott Fisher Company", whereas said patent should have been issued to "Elliott-Fisher Company, of New York, N. Y., a Corporation of Delaware", as assignee of the entire interest in said invention, as shown by the records of assignments in this office; and that the said Letters Patent should be read with this correction therein that the same may conform to the record of the case in the Patent Office.

Signed and sealed this 16th day of April, A. D. 1929.

(Seal)

M. J. Moore,
Acting Commissioner of Patents.
